UNITED STATES PATENT OFFICE.

HENRY E. LEAVITT AND ALBERT D. LANE, OF OAKLAND, CALIFORNIA.

COOLING APPARATUS.

1,194,518.

Specification of Letters Patent. Patented Aug. 15, 1916.

Application filed April 27, 1915. Serial No. 24,240.

To all whom it may concern:

Be it known that we, HENRY E. LEAVITT and ALBERT D. LANE, citizens of the United States, residing at Oakland, in the county 5 of Alameda and State of California, have invented certain new and useful Improvements in Cooling Apparatus, of which the following is a specification.

The present invention relates to refrigerating or cooling systems, and more particularly to that type of system wherein evaporation and absorption are employed.

The invention has for its principal objects to provide a system wherein a circulation of air is maintained and the same is passed through a series of ducts and also through several cooling stages and is thence caused to pass in proximity to the air contained within a chamber to withdraw the 10 heat therefrom by absorption; to provide a system wherein there is employed a fluid medium for lowering the temperature of the cooling air and which acts on the cooling air in its several stages of cooling; to 15 provide a system wherein there is maintained a positive circulation of the cooling fluid and air, so that the air and water after having absorbed the heat units from the air in the chamber will be rapidly removed and 20 replaced; and to provide a system which is simple in construction, is capable of being 25 efficiently operated at little cost, and is adapted for use generally where cooling systems are required.

With the above mentioned and other objects in view, the invention consists in the novel construction and combination of parts, hereinafter described, illustrated in the accompanying drawings and pointed out in 30 the claims hereto appended; it being understood that various changes in the form, proportion, size and minor details of construction within the scope of the claims may be resorted to without departing from the 35 spirit or sacrificing any of the advantages of the invention.

To more fully comprehend the invention, reference is directed to the accompanying drawings, wherein—

Figures 1 and 1^A form a view in side elevation of a car of the refrigerator type with an embodiment of our invention therein. Figs. 2 and 2^A form a view in transverse longitudinal section, taken near the top of 55 the car, disclosing the general arrangement of the circulating ducts and headers. Fig. 3

is a vertical sectional view taken on lines 3—3 of Figs. 1^A and 2^A. Fig. 4 is a diagrammatic view in perspective of the air circulating system, disclosing by arrows the 60 course of the air passing through the ducts and headers. Fig. 5 is a sectional view taken on line 4—4 of Figs. 1 and 2, viewed in the direction of the arrow. Fig. 6 is a sectional view of one of the ducts positioned within the inclosure, disclosing the fabric material therein and the feed pipe for supplying a cooling fluid to the fabric.

Fig. 7 is a view in section of one of the fluid supply pipes which coöperates with the 70 circulating air cooling ducts. Fig. 8 is a cross sectional view of a drier box for containing a suitable drying material and through which the cooling air is caused to pass when the same is very humid. 75

Referring more particularly to the drawings, wherein our invention is illustrated in connection with a refrigerator car of the well known type, and in the several views of which like characters of reference designate 80 corresponding parts,—1 indicates a suitable car body of the double walled refrigerator type, provided at opposite ends with suitable ice chambers 2, which communicate with the exterior of the car and are supplied with ice through door controlled openings 3 in the roof of the car. The upper portion of the wall of the ice compartments next to the chamber is insulated, which causes the air from the compartments to enter the chamber about midway of the height 85 thereof and thereby maintain a circulation. The ice in the chambers rests on the perforated flooring 4 and the drip or water from the melting thereof passes through pipes 5 connecting with an insulated tank 6 carried beneath the car, and said tank is formed with an overflow 7 connecting with a larger insulated tank 8 also carried beneath the car and provided with an overflow 9. It will 90 be apparent that the tank 6 receives the cold drip water directly from the ice compartments, and the warmer water in the tank 6 rises and overflows into the tank 8. 95

Mounted preferably on the roof 10 of the 105 car and extending longitudinally of the opposite side edges thereof are the tubular housings or casings 11 and 12. The housing 11 is open at its opposite ends, as at 13, and extending longitudinally within the same in 110 spaced relation to each other are the zig-zag ducts 14 and 15, each having at the opposite

portion of its opposite end an air inlet opening 16 controlled by a gate 17.

Extending longitudinally within the housing or casing 12, in spaced relation to each other, are the zig-zag ducts 18 and 19, one end of each of which connects through a duct extending into the interior of the car, with the respective headers 20 and 21 extending preferably transversely of the interior of the car adjacent the top thereof, and the opposite ends of said ducts 18 and 19 connect through ducts 22 and 23 extending from the wall of the casing or housing 12, with the closed ends of said ducts 14 and 15.

15 Suitable circulating ducts 24 and 25 connect the respective end headers 20 and 21 with a center header 26 from one end of which extends the outlet duct 27, preferably positioned between the double walls of the 20 car and opening at its lower end beneath the floor thereof. The interiors of the casings or housings 11 and 12 connect midway of their length through channels 27' with the center header 26, as in Fig. 4.

25 Communicating with the ducts 14 and 15 at a point immediately below their respective inlets 16 are the opposite ends of a suitable duct 28 having a perforated floor 29 therein, and said duct is provided centrally 30 of its length with a slide controlled opening 29'. The duct 28 is adapted to contain a quantity of calcium chlorid or other moisture absorbing material 30, and when it is desired to remove the moisture from the air 35 before the same enters the ducts 14 and 15, the slide gates 17 are closed and air is permitted to pass through the slide controlled opening 29' into the duct 28 and before the air enters the ducts 14 and 15 it is caused to 40 pass through the body of material 30.

The air circulating means or pump may be of greater capacity and speed than the capacity of the connected ducts, this arrangement causing air to circulate through 45 all ducts but at different speed, or the openings connecting the ducts may be progressively increased in proportion to the progressive increase of resistance of the flow of air therethrough, this arrangement insuring a 50 uniform circulation through all the connected ducts.

A circulating apparatus, preferably a suction fan 31, is positioned in the lower end 55 of the duct 27 and the same is mounted on a shaft 32 carried beneath the car or bracket 33, and driven by a connection 34 with the car axle 35. Suitable water pumps 36 and 37 are also mounted on the shaft 32 and the pump 36 connects through a pipe 38 with the pipe 5 near its juncture with the tank 6. From the pump 36 extends the supply pipe 39 which connects through branches 39' with the distributing pipes 40 slotted in their upper surface, as at 41, and formed in the 60 upper portion of the ducts 25. Suitable

absorbent material, preferably asbestos fabric 42, connects with the slotted outlet 41 of the pipes 40 and extends around the interior of the ducts 25, providing means whereby the water from the pipes 40 will 70 pass circumferentially of the ducts 25 and absorb the heat rising in the interior of the car and in contact therewith. The excess water passes longitudinally of the ducts 25 into the headers 20, 21 or 26 and is returned 75 therefrom through the pipes 43 to the tank 6.

An overflow 39² is provided in one of the branches 39' and the same drains into the center header 26. A pressure actuated valve 39³ is positioned in the overflow 39² and 80 enables a pressure to be maintained for forcing the fluid from the pipes 40.

Extending longitudinally of the ducts 14, 15, 18 and 19, are the pipes 44 provided with a longitudinal outlet groove in the lower 85 portion and in said groove is mounted a suitable wicking 44 which distributes the fluid over the upper surface of the ducts so that the same will be enveloped thereby and the air passing therethrough and thence 90 around will have the heat absorbed therefrom by the water. The water enveloping the ducts 14, 15, 18 and 19 drains into the housings or casings 11 and 12 and passes therefrom through pipes 45 which connect 95 with the tank 8. The cooling fluid is supplied under pressure from the tank 8 to the pipes 44 by pipes 46 which connect with the pump 37. In the upper portion of one of the pipes 46 is an overflow 47 communicating with one of the connections 45 and controlled by a pressure actuated valve 48, and this construction enables the cooling fluid to 100 be forced into the pipes 44 under pressure.

The pumps 36 and 37 are of such size and 105 capacity that when operating under normal speed they supply the cooling fluid to the outlets in the system thereof under sufficient pressure to insure the necessary distribution through the outlets to maintain the absorbent material associated therewith saturated. Any excess pressure in the pipes leading 110 from the pumps 36 and 37 caused by the increased speed of the pumps, due to an excessive speed of the car, is relieved by the pressure actuated valves 39³ and 48 which are adjusted to operate at a pressure slightly above that caused by a normal speed of the pumps and the water released by the opening thereof passes through the respective overflow 115 pipes 39² and 47 and is returned to the respective tanks 6 and 8.

Referring to Fig. 4, it will be observed 120 that when the suction device 31 is operated, air will be drawn into the opposite ends of the housing or casing 11, and also through the opposite ends of the zig-zag ducts 14 and 15. The air entering the opposite ends of the casing 11 will pass around the zig-zag ducts 14 and 15 for approximately one-half 125 130

of their length and will be cooled by the fluid enveloping the duct, and the cooled air will pass through the duct 27' into the header 26 and thence into the outlet 27. The air 5 passing in opposite directions in the respective ducts 14 and 15 will become chilled by the action of the cooling fluid surrounding the ducts and will pass from the respective ducts 14 and 15 into the respective headers 10 22 and 23 which communicate with the opposite end of the casing or housing 12 in which are positioned the ducts 18 and 19. The air entering the opposite ends of the housing 12 is divided, one-half passing into 15 the open end of and through the respective ducts 18 and 19 where the temperature thereof is again reduced by the action of the cooling fluid enveloping the ducts, and the other half passing around the ducts 18 and 20 19 is cooled by the fluid enveloping the ducts 18 and 19, and passes longitudinally of the housing 12 in opposite directions toward the center thereof, thence through the duct 27' into the header 26 and outwardly through the 25 outlet 27. The air after having traveled the length of the ducts 18 and 19 passes therefrom into the respective headers 20 and 21, thence through the ducts 24 and 25 where the temperature thereof is again reduced and into 30 the center header 26 from where it is caused to intermingle with the original quantity of air drawn into the opposite ends of the housing 11 and ducts 14 and 15.

The water from the tank 8 which is of the 35 higher temperature of that contained in the two tanks, is used in connection with the casings 11 and 12 and the ducts 14, 15, 18 and 19, and reduces the temperature of the air during the first two stages of cooling. 40 The water of lower temperature or that contained in the tank 6, and which has just melted from the ice, is employed in the third and last stage of cooling, and passes around the interior of the ducts 24 and 25, thereby 45 cooling the air in the car which contacts with the surface of the headers 20, 21 and 26 and the ducts 24 and 25.

It will be apparent that our apparatus is 50 designed to divide the quantity of air to be acted on during each successive cooling step and during the final cooling step when the same passes through the ducts 24 and 25, the water from the tank 6 will be in contact therewith thereby reducing the air to a low 55 temperature so that the majority of the heat units in the air of the chamber circulating around the ducts 24 and 25 will be removed thereby. The air contained within the chamber is maintained in constant circulation 60 within the chamber and is not removed or replaced by the outside atmosphere and thus maintained cool at the expense of the ice in the chambers 2, as is done in devices of this character now in use.

65 Under certain conditions the ice in the

chambers 2 may be dispensed with and the tanks 6 and 8 filled with water which is maintained in circulation through the respective systems of piping.

Should it be desired to ventilate the chambers, the air for this purpose may be supplied from any suitable source. 70

Having thus described our invention what we claim is:—

1. A cooling apparatus comprising a 75 chamber, a system of connected ducts provided with inlet and outlet openings without said chamber and said ducts contacting with the air in said chamber and through which cooling air is adapted to circulate, means for circulating air through said ducts, and means for supplying a cooling fluid to said ducts while the air is circulating therethrough. 80

2. A cooling apparatus comprising a 85 chamber to be cooled, a system of connected ducts provided with inlet and outlet openings without said chamber and through which cooling air is adapted to circulate toward the outlet, means for circulating air through said ducts, a portion of said ducts adjacent to said outlet extending within said chamber, and means for supplying a cooling fluid to the interior of certain of 90 said ducts.

3. A cooling apparatus comprising a 95 chamber to be cooled, a system of connected ducts provided with inlet and outlet openings without said chamber and through which cooling air is adapted to circulate toward the outlet, means for circulating air through said ducts, a portion of said ducts adjacent to said outlet extending within said chamber, and means for supplying a cooling fluid to the exterior of certain of 100 said ducts and to the interior of certain other of said ducts. 105

4. A cooling apparatus comprising a 110 chamber to be cooled, a system of connected ducts associated therewith and provided with air inlet and outlet openings without the chamber, means for circulating air through said ducts, said ducts being arranged to separate the air entering the inlet openings into a plurality of streams while passing therethrough and cause the same to pass through a single outlet opening, and means for supplying cooling fluid to said ducts to reduce the temperature of the air as it passes therethrough. 115

5. A cooling apparatus comprising a 120 chamber to be cooled, a system of connected air circulating ducts associated therewith and provided with air inlet and outlet openings without the chamber and including a 125 housing open at its opposite ends, and a plurality of ducts in said housing open at their opposite ends and connected at their opposite closed ends with ducts extending within the chamber, means for circulating 130

air through said ducts toward said outlet, and means for supplying a cooling fluid to the surface of said ducts in said housing.

6. A cooling apparatus comprising a chamber to be cooled, a system of connected air circulating ducts associated therewith and provided with air inlet and outlet openings without the chamber, means for circulating air through said ducts toward said outlet, a plurality of tanks for containing cooling water of different temperatures, and means for supplying the cooling water from said tanks to different portions of said system of ducts.

15 7. A cooling apparatus comprising a chamber to be cooled, an ice receiving compartment communicating with said chamber, a tank for receiving the drip from said ice receiving compartment, a system of connected air circulating ducts associated with said chamber and provided with air inlet and outlet openings without the chamber, means for circulating air through said ducts, and means for supplying cooling water from said tank for cooling the air as it passes through said ducts.

8. A cooling apparatus comprising a chamber to be cooled, an ice receiving compartment communicating with said chamber, a tank for receiving the drip from said compartment, a system of connected air circulating ducts associated with said chamber and provided with air inlet and outlet openings without the chamber, means for circulating air through said ducts, means for supplying cooling water from said tank for cooling the air as it passes through said ducts, and means for returning the cooling water to said tank.

30 40 9. A cooling apparatus comprising a chamber to be cooled, a system of connected air circulating ducts associated therewith and provided with air inlet and outlet openings, and including a housing exterior of the chamber and open at its opposite ends, and a plurality of ducts in said housing each provided at one end with a valve controlled opening and at their opposite ends communicating with ducts extending into the 45 chamber, means for circulating air through said ducts toward said outlet opening, a duct provided with a valve controlled opening and connecting at its opposite ends with the valve controlled ends of said first mentioned ducts, and a drying medium in said last mentioned duct and in contact with which the air entering the valve controlled opening thereof must contact before entering the first mentioned ducts.

55 60 65 10. A cooling apparatus comprising a car formed with an interior chamber and ice receiving compartments at either end thereof, a system of connected air circulating ducts extending within the chamber and provided with air inlet and outlet openings

exteriorly of the chamber, a plurality of tanks for receiving the drip from said ice receiving compartments, means for circulating air through said ducts, means for supplying cooling water from one of said tanks to that portion of said ducts arranged exteriorly of said chamber, means for supplying cooling water from another of said tanks to that portion of said ducts arranged interiorly of said chamber, and means for returning the cooling water to its respective tanks.

11. A cooling apparatus comprising a chamber to be cooled, a pair of casings arranged exteriorly of said chamber, one of said casings open at both ends, a pair of ducts mounted in each casing in spaced relation to the walls thereof, the ducts in each of said casings being open at one end and said open ends being arranged at opposite ends of said casings, valves controlling the open ends of the ducts in said open ended casings, the opposing end of each of said ducts communicating with the other of said casings, a pair of headers in said chamber and connected with the opposing end of the ducts in said last mentioned chamber, an outlet duct connecting said headers, a communication between each of said casings and said outlet ducts, and means for maintaining a circulation of air in said system.

12. A cooling apparatus comprising a car having supporting axles and wheels and formed with an interior chamber, a system of connected air circulating ducts extending within the chamber and provided with air inlet and outlet openings exteriorly of the chamber, a tank for containing a cooling fluid, a pump for circulating air through said ducts, a pump for supplying cooling water from said tank to said ducts, and a connection from one of said car axles for operating said pumps.

13. A cooling apparatus comprising a car having supporting axles and wheels and formed with an interior chamber, a system of connected air circulating ducts extending within the chamber and provided with air inlet and outlet openings exteriorly of the chamber, a tank for containing a cooling fluid, a pump for circulating air through said ducts, a pump for supplying cooling water from said tank to said ducts, a connection from one of said car axles for operating said pumps, and means for returning the cooling water to said tank.

14. A cooling apparatus comprising a chamber to be cooled, a pair of casings arranged exteriorly of said chamber, one of said casings open at both ends, a pair of ducts mounted in each casing in spaced relation to the walls thereof, the ducts in each of said casings being open at one end and said open ends being arranged at op-

- posite ends of said casings, valves controlling the open ends of the ducts in said open ended casings, the opposing end of each of said ducts communicating with the other 5 of said casings, a pair of headers in said chamber and connected with the opposing end of the ducts in said last mentioned chamber, an outlet duct connecting said headers, a communication between each of 10 said casings and said outlet ducts, means for maintaining a circulation of air in said system, and means for supplying a cooling fluid to said apparatus for cooling the air as it passes therethrough.
- 15 15. A cooling apparatus comprising a chamber, a duct provided with inlet and outlet openings without said chamber and said duct contacting with the air in said chamber and through which cooling air is 20 adapted to circulate, means for circulating air through said duct, and means for supplying a cooling fluid to said ducts.
16. A cooling apparatus comprising a chamber to be cooled, a system of connected 25 ducts provided with inlet and outlet openings without said chamber and through which cooling air is adapted to circulate toward the outlet, means for circulating air through said ducts, a portion of said 30 ducts adjacent to said outlet extending within said chamber, and means for supplying a cooling fluid to certain of said ducts.
17. A cooling apparatus comprising a 35 car having supporting axles and wheels and
- formed with an interior chamber, a system of connected air circulating ducts extending within the chamber and provided with air inlet and outlet openings exteriorly of said chamber, means for supplying a 40 cooling fluid to said ducts, means for causing a circulation of air through said ducts, and driving connections associated with one of said supporting members for operating said last mentioned means. 45
18. A cooling apparatus comprising a chamber, a duct provided with inlet and outlet openings without said chamber and said duct contacting with the air in said chamber and through which cooling air is 50 circulated, and means for reducing the temperature of said duct. 55
19. A cooling apparatus comprising a chamber, a system of connected ducts provided with inlet and outlet openings without the chamber, certain of said ducts extending within said chamber, means for circulating air through said ducts, and means for reducing the temperature within the ducts in said chamber to a lower degree 60 than the temperature in the ducts exteriorly of said chamber.

In testimony whereof we have signed our names to this specification in the presence of two subscribing witnesses.
